I claim:

The ornamental design for a seat for a velocipede, substantially as shown and described.
